UNITED STATES PATENT OFFICE

HOWARD L. KRUM, OF KENILWORTH, ILLINOIS, ASSIGNOR TO TELETYPE CORPORATION,
OF CHICAGO, ILLINOIS, A CORPORATION OF DELAWARE

ELECTRIC SELECTOR MECHANISM

Original application filed July 16, 1926, Serial No. 122,808. Patent No. 1,783,382, dated December 2, 1930.
Divided and this application filed September 26, 1930. Serial No. 484,517.

The present application is a division of an application filed by me in the United States Patent Office July 16, 1926, Serial No. 122,808, which resulted in Patent No. 1,783,382, Dec. 2, 1930.

The invention relates to electric selector mechanism such as used for controlling the operation of telegraph receivers, printers or the like, and which comprises a set of selectors that are positioned or conditioned in different combinations in response to code signals comprising permutations of two different electrical conditions extending through a definite number of successive time intervals. More particularly, the invention relates to a selector mechanism in which the selectors are mechanically set under the joint control of a locally driven member or shaft, and a member which is selectively vibrated under control of a magnet which responds to the electrical conditions of the code signals.

As pointed out, in the above noted parent application, such single magnet selector mechanisms having mechanical distributors possess many advantages over those using electrical distributors, but that in such mechanical selector mechanisms, it is desirable to provide means for insuring that the setting of the selectors be determined at definite points or at very brief spaced intervals in the cycle of operation of the locally actuated distributing member so that such points may coincide with and the setting of the selectors be determined by the mid-portions or most effective portions of the intervals of the received signals. Also, as set forth in the parent application, this desirable result is effected by employing a locking device operating in synchronism with the locally driven member or mechanical distributor and which is arranged to engage the member vibrated under control of the selector magnet at definitely spaced points in the cycle of operation of the selector to thereby predetermine the setting of the selectors at such points and hold the controlling member against vibration during the actual setting of the selectors.

The improvement is fully set forth in the foregoing parent application and the present

application relates more particularly to the type of selector mechanism such as set forth in the prior application of E. E. Klein-schmidt, Serial No. 704,022, filed April 3, 1924, which resulted in Patent No. 1,811,131, June 23, 1931, and in which a rotary member having a spiral series of setting cams or projections is locally driven in synchronism with the received signals and is variably vibrated to determine setting of selectors under control of a magnet which responds to the code signals.

The present invention consists in features of improvement hereinafter set forth, illustrated in the preferred form in the accompanying drawing and more particularly pointed out in the appended claims.

In the drawing:

Fig. 1 is a view illustrating the application of the present improvement to the selector mechanism shown in the above noted Patent No. 1,811,131, parts being shown in elevation and parts in section on the line 1—1 of Fig. 2.

Fig. 2 is a cross section on line 2—2 of Fig. 1.

As set forth in the said Patent No. 1,811,131, the selector mechanism comprises a set of notched permutation bars 10, five in number, in the form shown, which select and control the operation of a set of actuating bars 11 and which permutation bars are in turn controlled by a set of pivoted selecting fingers 12.

The latter are pivotally mounted at their lower ends upon a stud 13 fixed to a bracket 14 and springs 15 tend to hold the upper ends of the levers (which are relatively offset as shown in Fig. 2) against a stepped stop plate 16 and in line with lugs 17 on the corresponding permutation bars. The primary selectors or fingers 12 are set or shifted from normal position by a spiral series of cams or pins 18 mounted on a shaft or barrel 19. The latter is rotated during each operation by a continuously driven motor shaft 20 which is connected to a short shaft 21 by a friction clutch 22. Shaft 21 has a forked extension 23 which is engaged by a pin 24 on the end of the shaft or barrel 19. A reduced exten-

sion 25 on the latter extends within the bore of the shaft 21 and a spring 26 coiled about this extension tends to shift the pin barrel to the left and holds a reduced extension 27 on its other end (which is journaled in the bracket 14) against the armature lever 28 of the magnet 29. A spring 30 tends to hold the armature lever in engagement with a stop screw 31, but the magnet is normally energized and holds the armature lever against a stop screw 32 and the barrel or cam shaft in its right-hand position with spring 26 compressed.

In its normal right-hand position, the pins or cams 18 are in alignment with the primary selectors or fingers 12, but when the magnet is deenergized and the cam shaft shifted to the left by spring 26, these pins are out of alignment with the corresponding levers.

When in alignment therewith and rotated past lugs 33 on the corresponding fingers, the latter will be shifted to the left (when viewed as in Fig. 2) to move their upper ends out of line with the lugs 17 of the corresponding permutation bars, and any selected lever will be held in shifted position by the engagement of a latch 34 with a shoulder 34' on the lever.

Normally, as stated, the magnet is energized and in this position a stop pin 35 engages a stop lug 36 on the bracket. It is noted that the latches 34 are of such width and so located that each of them, except that corresponding to the first selector or finger, is adapted to be engaged by the corresponding pin or cam 18 whether the cam shaft is in its right-hand or left-hand position. The latch of the first selecting finger is in the path of movement of the stop pin 35.

During the starting interval or unit, which precedes the selecting intervals of each signal, magnet 29 is deenergized and the shifting of the cam shaft 19 to the left disengages the stop pin 35 from the lug 36 so that the rotation of the cam shaft is initiated. During the remainder of the starting interval, the stop pin will engage and release the first latch 37 so that the first selecting lever is restored if it has been shifted during the previous selection. Thereafter the latches 34 are successively released by the corresponding pins 18 and the cam shaft during its rotation is also vibrated by the armature lever 28 in response to the different electrical conditions extending through the selecting intervals or units of the signal. If the magnet is energized and the cam shaft in right-hand position as the pins or cams pass into operative relation with the lugs 33 on the corresponding selectors, the latter will be shifted and held in shifted position by the latches 34; but if the magnet is deenergized at any such interval, the pin or cam will clear the bevel 33 of the corresponding selector and leave the latter in its normal position. At the end of any printing operation, as described in the

above noted Patent No. 1,811,131, the permutation bars 10 are restored and the setting of the primary selectors 12 is transferred thereto.

To lock the cam shaft against vibrating movement at definite, uniformly spaced points during each selecting cycle, a locking bell crank lever 37 is pivotally mounted upon a portion 38 of the frame and a spring 39 connected to the lever tends to hold a roller 40 thereon in engagement with a cam disc 41 fixed to the cam shaft or pin barrel 19. The latter has a series of depressions into which the roller 40 drops at uniformly spaced intervals during each rotation of the cam shaft, to bring a knife-edge 42 on the locking lever into engagement with a beveled edge disc 43 on the cam shaft. In this way the cam shaft is locked either in its right or left-hand position just before it passes through any of its selector operating positions and the armature lever 28 is thereby rendered ineffective during the setting of the selectors. As indicated, the roller 40 is of sufficient width to properly engage the cam disc 41 in either of the positions of the axially movable or vibratory cam shaft.

With the improved arrangement, the selection or setting of the primary selectors or fingers 12 is determined at definitely spaced points in the setting cycle and which, by the orientation or adjustment of the stop for the rotatable member, can be caused to register with the mid-portions or most effective portions of the selector intervals of the signals.

Changes may be made from the details set forth without departing from the scope of the appended claims.

I claim as my invention:

1. In an electric selecting mechanism, a set of selectors adapted to be conditioned in different combinations, a rotary member vibrated axially in response to receive signals to determine the setting of said selectors, and associated means for holding said member against axial movement at definite spaced points in the setting cycle and during the following intervals in which the setting of the selectors is effected.

2. In a selector mechanism for telegraph receivers, a set of selectors, a rotary member for effecting the setting of said selectors, means controlled by received impulses for axially moving said rotary member to determine the setting of said selectors, and means for holding the rotary member in one or the other of its selecting conditions during the intervals in which the setting of the selectors is effected.

3. In a selecting mechanism for telegraphs, a set of selectors, a rotary, locally driven member for effecting the setting of said selectors, an electro-magnet responsive to received impulses, for controlling the axial movement of said rotary member between

- two different selecting conditions, and associated means effective at definite, spaced points in the setting cycle for maintaining said member in one or the other of its selecting conditions during the intervals in which the setting of the selectors is effected. 70
4. In a selector mechanism, a set of selectors, an electro magnet, a locally driven rotary member for effecting the setting of said 100 selectors, means controlled by said magnet for axially moving said rotary member to determine the setting of said selectors, a disc and a notched cam on said rotary member, and a locking device vibrated by said cam and cooperating with said disc to hold said rotary member against axial movement. 75
5. In a selector mechanism, a set of selectors, a rotary, axially movable, selector actuator, a magnet for controlling the axial vibration of said actuator between two selecting 20 conditions to thereby determine the setting of said selectors, and means effective at uniformly spaced points in the setting cycle for holding said member in one or the other 25 of its selecting conditions. 80
6. In a selector mechanism, a set of selectors, an electro magnet, a locally driven rotary member for effecting the setting of said 30 selectors, means controlled by said magnet for axially moving said rotary member to determine the setting of said selectors, a disc and a notched cam on said rotary member, and a locking device vibrated by said cam and cooperating with said disc to hold said rotary 35 member against axial movement, said disc and locking device having cooperating beveled edges and said locking device being spring-pressed toward said cam and disc. 85
7. In a selecting mechanism for telegraphs, 40 a set of selectors, a locally driven rotary member having a series of spaced cams for setting said selectors, a magnet responsive to received impulses, means controlled by said magnet for longitudinally moving said 45 rotary member to selectively determine the setting of said selectors by said cams, and means for holding said member in one or the other of its selecting conditions during the intervals in which said cams are in operative 50 relation with the corresponding selectors. 90
8. In a telegraph receiver, a shaft, means operative upon the rotation of said shaft for effecting a series of selecting operations, means responsive to received impulses for 55 moving said shaft longitudinally to variably determine said selecting operations, and means effective upon each such movement for holding said shaft against further longitudinal movement for predetermined intervals 60 thereafter. 95
9. In a telegraph receiver, a rotating device, locally actuating means for rotating said device, means controlled by received impulses for selectively positioning said device, means 65 effective at definite spaced points in the cycle 100 of operation of said rotating device for holding the same in selected condition for predetermined intervals, and a set of selectors conditioned by the rotary movement of said device during such intervals. 105
10. In a receiver for telegraphs, a set of 110 selectors, a device locally rotated to effect the setting of said selectors in different combinations, said rotating device being operatively responsive to received current impulses and means for rendering said device unresponsive to the current impulses at definite spaced intervals in its selector setting cycle. 115
11. In a receiver for printing telegraphs, a set of selectors, a shaft having a series of selector setting cam members, means for rotating said shaft to bring the cam members into operative relation with said selectors, means for selectively operating said shaft in response to received current impulses, and means for rendering said shaft unresponsive to received impulses during the intervals in which said cam members are in operative 120 relation with the corresponding selectors. 125
12. In a telegraph receiver, a set of cam members, a set of selectors, means whereby said cam members are successively responsive to received current impulses for variably operating said selectors, and means for rendering said cam members unresponsive to the current impulses during the intervals in which said cam members are in operative relation with said selectors. 130
13. In a telegraph receiver, selecting members, a shaft having a plurality of cam members, each operative upon one of said selecting members, means for rotating said shaft to bring said cam members successively into operative relation with said selecting members, means responsive to received current impulses for positioning said cam members as they are brought into operative relation with the corresponding selecting members, and means effective upon each positioning of said cam members for locking each cam member to complete its operation. 140
14. In a telegraph receiver, a set of primary selectors, a set of actuating members each operative upon one of said selectors, locally driven means for bringing said actuating members and said selectors successively into operative relation, means responsive to received current impulses for effecting a relative movement between the set of actuating members and the set of selectors to determine the setting of the selectors, and means for rendering the current impulses ineffective at definite spaced points in the operating cycle and during the intervals in which the actuating members are operative upon the corresponding selectors. 150
15. In a printing telegraph receiver, a set of 155 selectors, a rotating shaft, means operated thereby for setting said selectors, means for moving said shaft longitudinally to deter- 160

mine the setting of said selectors in response to received impulses, and means for locking said shaft against longitudinal movement at predetermined points in its rotary path of movement.

16. In a telegraph receiver, a set of selectors, an actuating member locally rotated to effect the setting of said selectors, means responsive to received current impulses for effecting a relative vibratory movement between said member and the set of selectors in a direction axially of said member and locally actuated means for rendering the current impulses ineffective at definite spaced points in the operating cycle and during the intervals in which the actuating member is operative upon the selectors.
